UNITED STATES PATENT OFFICE.

FOREST R. LA PLANTE, OF GUNNISON, COLORADO.

SPARK-PLUG.

1,217,784.

Specification of Letters Patent. Patented Feb. 27, 1917.

Application filed September 19, 1916. Serial No. 120,996.

To all whom it may concern:

Be it known that I, FOREST R. LA PLANTE, a citizen of the United States, residing at Gunnison, in the county of Gunnison and State of Colorado, have invented new and useful Improvements in Spark-Plugs, of which the following is a specification.

This invention relates to spark plugs for ignition circuits, the broad object in view being to produce a plug and means used conjointly therewith, whereby the direction of flow of the electric current through the plug and to the ground may be reversed or caused to travel in the opposite direction for the purpose of maintaining the points of the electrodes in a clean condition and preventing the accumulation of material between the same which would ultimately bridge the gap and eliminate the spark.

With the above and other objects in view, the invention consists in the construction, combination and arrangement, herein fully described, illustrated and claimed.

In the accompanying drawing:

Figure 1 is a diametrical section through a spark plug embodying the present invention.

Fig. 2 is a detail perspective view of the primary switch.

Fig. 3 is a similar view of the washer used in conjunction with the switch.

Fig. 4 is an end view of the core.

Fig. 5 is a detail perspective view of the secondary switch.

Fig. 6 is a fragmentary section showing the relation of the secondary switch to one of the electrodes.

Referring to the drawings 1 designates the shell or main body of the plug which is externally threaded at 2 to enable the same to be screwed into an engine cylinder in the same manner as the ordinary spark plug now in common use. The shell or body 1 may, of course, be made of any size and threaded in accordance with any standard spark plug.

The body 1 is counterbored in its inner end to form an annular shoulder 3 against which bears the corresponding annular shoulder 4 formed exteriorly of the core 5 of the plug, said core being composed of any suitable insulating material such as porcelain, fiber or raw-hide, the shoulders 3 and 4 preventing the core from being blown outwardly through the shoulder or body 1 when

an explosion occurs in the combustion chamber of the cylinder.

The outer end of the body 1 is counterbored and internally threaded as shown at 6 to receive a packing nut or gland 7, packing material 8 such as asbestos being placed in the inner portion of the counterbore of the body 1 so as to prevent leakage between the core and shell.

Extending longitudinally through the core 5 and in substantially parallel relation to each other, are electrodes 8 and 9 each of which may constitute the power electrode as will hereinafter appear. At their inner extremities, the electrodes 8 and 9 are deflected toward each other to leave a gap 10 of any desired width. The opposite end portions of the electrodes are bent or extended outwardly in opposite directions to form contact ends 11 and 12 the same projecting slightly beyond the outer surface of the core 5.

13 designates the binding post of the plug and 14 a circuit terminal in electrical contact therewith. 15 represents a binding nut for the terminal 14 and 16 represents a jam or lock nut, both of said nuts being threaded on the binding post 13 the inner end of which is anchored in the body of the core 5 as shown.

17 represents a switch consisting of a plate or disk-like body which is formed with a central hole to receive the binding post 13 and 18 represents a nut threaded on the post 13 to prevent the switch from turning or bearing tightly against said switch. The switch comprises an inwardly extending spring arm 19 which normally lies in contact with one of the end portions 11 or 12 of the electrodes 8 and 9 as clearly illustrated in Fig. 1. Between the switch 17 and the adjacent end of the core 5 there is arranged a washer 20 which is held in a certain definite relation to the core 5 by means of a diametrically extending hollow rib 21 formed on the washer and having its convex face received in a diametrical seat in the core 5. The switch body 11 is formed with a corresponding rib 22 which is received in the groove thus formed in the washer 20. The switch and washer are thus maintained in a certain definite relation to each other and to the end of the core, insuring contact between the switch arm 19 and one of the electrodes. By loosening the nuts at the outer

end of the plug, the switch 19 may be sufficiently loosened to be turned by hand through an arc of 180° for the purpose of bringing the switch arm 19 into contact with the other electrode.

When the switch arm 19 is in contact with one of the electrodes, the other electrode is in contact with the spring arm 23 of another switch 24 the body of which is in the form 10 of a disk or plate having a central opening to receive the core 5. The end portion of the spring arm 23 is preferably grooved as indicated at 25 to prevent the same from becoming accidentally disengaged from the 15 electrode with which it lies in contact. A nut 26 serves to clamp the switch 24 against a shoulder 27 on the packing nut or gland 7 hereinabove referred to.

From the foregoing description taken in 20 connection with the accompanying drawing, it will now be understood that by shifting the primary and secondary switches 17 and 24 through an arc of 180° or by turning the core 5 through the same number of degrees, 25 the direction of flow of the electric current will be reversed and thereby any particles of carbon, metal or other material which may have accumulated on one of the electrodes will be forcibly ejected, propelled or 30 driven therefrom, thereby keeping the gap free for the jumping of the spark across the same. In this way the life of the plug is greatly prolonged and the same may be easily maintained at its full efficiency, preserving 35 the electrical conductivity of the electrodes. The plug may be tested by a screw driver or other implement in the same manner as the present day spark plug used in 40 conjunction with internal combustion engines.

I claim:

1. A spark plug embodying two electrodes insulated from the spark plug casing, and switching means connected with said plug for reversing the direction of flow of an ignition circuit through said electrodes. 45

2. A spark plug embodying two electrodes insulated from the spark plug casing and arranged to form a spark gap adjacent to one end of the plug, a primary switch for 50 conducting the current to one electrode, means for shifting said switch from one electrode to the other, and means for grounding the electrode not in contact with said switch.

3. A spark plug embodying two electrodes 55 insulated from the spark plug casing and arranged to form a spark gap adjacent to one end of the plug, a primary switch for conducting the current to one electrode, means for shifting said switch from one electrode to the other, and means for grounding 60 the electrode not in contact with said switch, the last named means consisting of a secondary switch adjustable from contact with one electrode into contact with the other 65

4. The combination of a spark plug having two electrodes insulated from the spark plug casing forming a gap adjacent to one end of the plug and having their opposite ends extended outwardly through the side walls of the plug core, a primary switch adjustable for the purpose of conducting the current to the last named end of either electrode, and a secondary switch adjustable for the purpose of receiving the current from the last named end of either electrode. 70 75

In testimony whereof I affix my signature.

FOREST R. LA PLANTE.
